VELOCITY MODULATION ELECTRON
DISCHARGE APPARATUSEugene Feenberg New York, N. Y., assignor to
Sperry Gyroscope Company, Inc., a corporation
of New York

Application December 14, 1943, Serial No. 514,220

10 Claims. (Cl. 315—6)

1 The present invention relates to the art including ultra high frequency electron discharge devices, especially of the velocity modulation type in which electrons of an electron beam are periodically varied in velocity at an ultra high frequency, and are then permitted or caused to velocity group or form bunches by the action of the faster electrons overtaking the slower electrons. Ultra high frequency energy of the input frequency or a harmonic thereof may then be extracted from the bunched or variable current beam. Such devices serving as amplifiers or oscillators are discussed in Varian Patent No. 2,242,275, issued May 20, 1941, and, when serving as modulators or frequency multipliers, are disclosed in Varian and Hansen Patent No. 2,281,935, issued May 5, 1942.

During the bunching action in such devices, certain effects take place which tend to impair the ability of the bunched or density-modulated beam to give up high frequency energy to the output circuit. One of these effects is caused by the mutual repulsion of the similarly charged and unneutralized electrons of the non-uniform beam. This repulsion causes a delay in the formation of the bunches by electrons at the center of the beam with respect to similar bunch formation at the edges of the beam. That is, a longer drift distance is required at the center of the beam to produce a given electron density by velocity grouping than is required at the edges of the beam. Also, for maximum energy extraction from the beam, the electron density in a predetermined plane transverse to the beam at the location of the energy extraction circuit is greater at the edges of the beam than at the center, and so the ability of the centrally located electrons to deliver high frequency energy to the output circuit is reduced, and the maximum value of the instantaneous beam current or average electron density across the beam cross-section is lowered, leading to lowered output. This effect is especially noticeable in the case of frequency multipliers or harmonic generators of the type shown in Patent No. 2,281,935 mentioned above, since the sharpness or peak current intensity of the bunch, and the consequent harmonic frequency content of the beam current passing through the output circuit grids, are materially reduced.

According to the present invention this non-uniform bunching effect is substantially prevented or minimized by modifying the action of the velocity modulating grids or electrodes so as to act differently upon the central electrons of the

beam. By increasing the velocity modulating effect upon the central electrons with respect to the electrons at the edges of the beam, and by the proper amount, the non-uniformity of the bunches arriving at the output electrodes can be made substantially zero. Thus, the entire electron beam passing through the output grids will have equal electron density over its entire cross-section. By properly positioning the output grids

10 along the beam, as by choice of the drift tube length, this electron density can be made to have the optimum value to produce amplification of the input energy or to produce frequency multiplication, in the manner mentioned in the above-
15 discussed Patents Nos. 2,242,275 and 2,281,935.

Accordingly, it is an object of the present invention to prevent or minimize the non-uniformity of the electron bunches in velocity modulation and velocity grouping electron discharge

20 devices.

It is another object of the present invention to overcome the harmful effects of longitudinal debunching in an electron beam having variable electron density therealong.

25 It is a further object of the present invention to provide improved velocity modulation electron discharge apparatus in which electrons at the center of the beam are velocity modulated differently from those at the edges of the beam.

30 It is a further object of the present invention to provide improved velocity modulation electron discharge apparatus of the frequency multiplier type in which the harmful effects of non-uniform electron bunches or longitudinal debunching are minimized or substantially prevented.

It is another object of the present invention to provide improved electron beam velocity modulating apparatus utilizing a pair of electron-permeable velocity modulating electrodes having different spacings at different portions of the electron beam passing therethrough.

Other objects and advantages will become apparent from the following specification, taken in connection with the accompanying drawings, wherein

50 Fig. 1 is a schematic diagrammatic representation of a conventional form of velocity modulation frequency multiplier apparatus useful in explaining the principle of the present invention.

Fig. 2 shows a graph of the peak electron density distribution across the drift tube at various locations along the drift tube of the device of Fig. 1.

55 Figs. 3, 4 and 5 show similar diagrammatic

representations of the velocity modulating portion of the device of Fig. 1, but incorporating the present invention.

Referring to Fig. 1, there is shown a conventional frequency multiplier velocity modulation device, comprising a pair of cavity resonators 11 and 12 separated by a conductive tube 13 forming a field free drift space. Resonator 11 includes a pair of electron-permeable electrodes or grids 14 and 15 as part of the conductive enclosing walls thereof. Resonator 12 similarly includes a pair of electron-permeable electrodes 16 and 17. These grids 14, 15, 16, 17 may be mesh grids or formed by radial or parallel slats, or may be omitted entirely in some forms of the device. A beam of electrons is projected by means of an accelerating battery or other accelerating voltage source 18 from a cathode 19 through the first or velocity modulating gap defined by grids 14 and 15, then through the drift space within tube 13, then across the output or energy extracting gap defined by grids 16 and 17, and is finally collected on the grounded conducting wall 21 of the device, or by a separate collecting electrode. The entire apparatus may be evacuated or enclosed in an evacuated envelope, or may have only the electron path evacuated.

Ultra high frequency energy of the operating angular or radian frequency ω , to which resonator 11 is tuned, is supplied to resonator 11 by way of a suitable input coupling such as a concentric transmission line 22 and a coupling loop 23 coupling line 22 to the electromagnetic field within resonator 11. In this way resonator 11 is excited to oscillate at the frequency ω , and a corresponding alternating electric field is impressed across grids 14 and 15. This field periodically alters the velocity of the electrons of the beam emitted from cathode 19 and thus velocity modulates the electron beam. The velocity-modulated electrons then travel down the length of drift tube 13, wherein the faster electrons overtake the slower electrons, so that some portions of the beam have increased electron density, while other portions have decreased electron density. In this way the beam becomes density-modulated or bunched and contains a high harmonic content by the time it reaches grid 16. The passage of this bunched beam between grids 16 and 17 then delivers ultra high frequency energy of a harmonic $n\omega$ of the frequency ω to the resonator 12 tuned to this harmonic frequency. Energy may be extracted from resonator 12 by a similar coupling loop 25 and output transmission line 24 to supply any desired type of load. The device thus far described therefore serves as a frequency multiplier for ultra high frequencies, as is described in Patent No. 2,281,935. If resonator 12 is tuned to the fundamental frequency ω , the device serves as an amplifier, as in Patent No. 2,242,275. In such case, if desired, the device may also serve as a regenerative oscillator by coupling or feeding back energy from resonator 12 to resonator 11. In this case the input connection 22 may be omitted. In devices of the type just described, the mutual repulsion of the electrons of the beam produces an effect known as longitudinal debunching. That is, the tendency of the faster electrons to overtake the slower electrons is opposed to some extent by the mutual repulsion of the similarly charged electrons. This effect has been found to be more marked at the center of the beam than at the edges of the beam, so that the formation of the bunches,

or the increasing of electron density in the beam, is delayed at the center of the beam with respect to the edges of the beam. This phenomenon is believed caused by the induction of image charges on the inner surface of the drift tube which travel down the drift tube along with the electron bunches and tend to neutralize the electron charges at the edges of the beam, so as to prevent longitudinal dispersion of these outermost electrons. At the center of the beam, however, the effect of the image charges is greatly reduced, so that the longitudinal debunching between the similarly charged electrons is not prevented to any substantial extent.

This debunching phenomenon is indicated in Fig. 2, which shows the peak electron density distribution across the drift tube at several locations A—A, B—B and C—C along the drift tube, at instants when the electron density at these points is maximum. Thus, at location A—A along drift tube 13, in Fig. 1, the velocity-modulated electrons have had but little opportunity to become bunched, and accordingly the peak electron density is only slightly larger than the average electron density which, in turn, is equal to the electron density of the beam before electron velocity modulation thereof. As shown by curve 31 of Fig. 2, this peak density is substantially the same over the entire cross-section of the drift tube.

At the location B—B, the bunching process has proceeded further, so that the peak electron density is substantially greater than the average electron density. Also, the effects of longitudinal debunching are beginning to become apparent, so that the electron density at the center of the beam is slightly less than that at the edges of the beam, as shown by curve 32.

Curve 33 shows the electron density distribution at line C—C within the catcher resonator 12, where the bunching process is at a maximum so that the peak electron density is greatly increased. However, the peak electron density is much greater at the edges of the beam than at the center of the beam because of the longitudinal debunching effect, leading to decreased efficiency, because the peak beam current, averaged across the beam, is lowered by the non-uniform bunching.

The loss in efficiency resulting from this non-uniform bunching process is considerably greater in frequency multipliers, such as shown in Fig. 1, than in simple amplifiers of the type shown in Patent 2,242,275. Also, the decrease in efficiency becomes greater for high multiplication ratios. Since such frequency multipliers may have multiplication ratios as high as 10 to 20, the harmful effects of non-uniform bunching are multiplied to that extent.

In accordance with the present invention, this loss in efficiency is minimized by substantially preventing non-uniformity of the bunch at the catcher or output grids 16 or 17, either in amplifier or oscillator devices such as in Patent No. 2,242,275, or in frequency multiplier devices such as in Fig. 1. For this purpose the electrons at the center of the beam are acted upon more strongly by the input wave than the electrons at the edges of the beam, so as to produce a greater amplitude of velocity modulation and thus overcome the opposing debunching tendency due to charge repulsion. The tendency for the electrons to bunch depends in part on their transit time through the velocity-modulating grids. An increase in this transit time in devices of the present

type produces a decreased tendency to bunch, while a decrease in transit time produces sharper bunching. In the present invention, the debunching at the center of the beam is substantially prevented by increasing the tendency of the center electrons to bunch, in relation to the outer electrons. This may be done in the manner shown in Fig. 3, which illustrates the velocity modulating portion of the device of Fig. 1, modified in accordance with the present invention.

Thus, instead of utilizing the customary parallel grids 14 and 15 as in Fig. 1, or other electrodes, these grids are now made to have variable spacing across the electron beam. As shown in Fig. 3, the grid 14' may remain substantially planar. Grid 15', however, is made to bow inwardly, so that the separation between grids 14' and 15' at the center of the beam is less than that at the edges of the beam. Preferably, grid 15' is made axially symmetrical with respect to the axis of the beam. In this way the transit time for the central electrons is reduced, leading to sharper bunching to overcome the tendency to debunch. By proper choice of the grid separation or gap as a function of radial distance from the beam center, the bunch arriving at the energy extracting gap may be made substantially uniform. Grids 16 and 17, therefore, may remain of the conventional type disposed in parallel planes.

I have discovered that a highly preferred form of the invention has a modulating grid separation s at a distance y from the beam axis which obeys the following relation:

$$\frac{s}{s_a} = 1 - k \left(1 - \frac{y^2}{a^2} \right)$$

where s_a is the grid spacing at the edge of the beam, y is the distance from the beam axis, and k is an experimentally determined constant. Where the electron beam nearly fills the drift tube, an approximate value for the factor k can be given by the formula

$$k \approx \frac{240L^2}{V\theta^2} \left[1 + \frac{2}{\pi^2} \left(\frac{\lambda}{a} \right)^2 \beta^2 \right] \beta a^2$$

in which L is the length of the field-free drift space; θ is the transit angle in radians through the velocity modulating gap at the edge of the beam; λ is the wave length; a is the radius of the beam; β is the ratio of electron velocity to the velocity of light; V is the unidirectional accelerating voltage; and I is the average electron beam current. It will thus be seen that the preferred form of grid 15' is essentially in the form of a paraboloid of revolution having an axis concentric with that of the beam.

Instead of bowing grid 15' inwardly, as shown in Fig. 3, it will be clear that grid 15' may be retained planar, as shown at 15''' in Fig. 4, while grid 14' is here bowed inwardly as shown at 14'' to provide the required variable spacing.

Also, both grids 14 and 15 may be made non-planar, as shown in Fig. 5, wherein both grids 14''' and 15''' are bowed inwardly while maintaining the desired variation in spacing over the cross-section of the beam. This is preferable, since then no radial acceleration is imparted to the electrons.

It should be understood that the drift space in tube 13 is substantially free of any portion of the alternating electromagnetic field existing within the resonators 11 and 12 due to the oscillations therein. For this reason this drift space is known as the field-free drift space, and is designated as such herein.

Preferably, the grids used in the present invention are of the mesh or lattice type, such as knit or stocking grids, to permit bowing to the proper curvature. However, as an approximation, grids formed by generally radial, but conically disposed slats may be used.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. High frequency apparatus comprising a pair of adjoining electron permeable electrodes defining a gap therebetween, a tuned circuit connected to said electrodes and adapted when excited to impress an alternating electric field between said electrodes, a second pair of electron permeable electrodes defining a second gap, a second tuned circuit similarly connected to said electrodes, conductive means connecting one electrode of each of said pairs together and providing a field-free drift space between said gaps, means aligned with said electrodes for projecting an electron beam successively through one of said gaps, said field-free space and the other of said gaps, said first pair of electrodes having a spacing varying parabolically from the center of the path of said beam to the edges of said beam path.

2. High frequency apparatus comprising means for producing an electron stream, first resonant circuit means along the path of said stream and adapted to produce an oscillating electric field at a predetermined point of said stream path to modulate the velocity of the electrons of said stream, means along said stream path for causing said electrons to form into bunches, and means along said stream path for extracting energy of a frequency harmonically related to the frequency of said field, said first tuned circuit means including a pair of electron-permeable electrodes along said stream path defining a gap through which the stream is passed and having non-uniform spacing across the cross-section of said stream which varies parabolically with respect to radial distance outward from the center of the path of said stream.

3. Apparatus as in claim 2, in which both of said electrodes are non-planar.

4. Apparatus as in claim 2, in which one of said electrodes is disposed substantially in a single plane and the other of said electrodes is formed as a paraboloid of revolution coaxial with said beam.

5. High frequency apparatus comprising a first cavity resonator having a pair of electron-permeable walls, a second cavity resonator tuned to a harmonic of the resonant frequency of said first cavity resonator and having a further pair of electron-permeable walls, and means aligned with said wall for projecting an electron beam successively through said resonators by way of said walls, said first pair of walls having a spacing across the cross-section of said beam varying substantially parabolically with respect to radial distance from the center of the path of said beam.

6. High frequency apparatus for frequency multiplication comprising means for producing an electron beam, means along the path of said beam for velocity modulating said electron beam at a predetermined frequency, and means along said beam path including a resonant circuit tuned

to a harmonic of said predetermined frequency for extracting harmonic frequency energy from said modulated beam, said velocity modulating means including a pair of smoothly curved grids in said beam path having a spacing increasing curvilinearly from the center of the beam outward, thereby minimizing loss in efficiency due to longitudinal debunching of said modulated electron beam at said energy extracting means.

7. High frequency apparatus comprising means for producing an electron beam, means along the path of said beam for velocity modulating said electron beam at a predetermined frequency, means along said beam path for causing said modulated beam to become bunched, and means along said beam path including a resonant circuit tuned to a harmonic of said predetermined frequency for extracting harmonic energy from said bunched beam, said velocity modulating means including a pair of smoothly curved grids in said beam path having a spacing increasing curvilinearly from the center of the beam outward, thereby minimizing non-uniformity of said electron bunches at said energy extracting means.

8. A velocity modulation electron discharge apparatus comprising a cavity resonator having a pair of juxtaposed electron permeable walls defining a gap through which an electron beam may be passed, said permeable walls having a spacing

varying parabolically with respect to radial distance from the center thereof.

9. Apparatus as in claim 8, wherein one of said electrodes is substantially planar and the other of said electrodes is substantially in the form of a paraboloid of revolution having its axis perpendicular to said first electrode.

10. A velocity modulation electron discharge apparatus comprising a cavity resonator having a pair of juxtaposed electron-permeable walls defining a gap through which an electron beam may be passed, both of said walls being non-planar and having a relative spacing varying parabolically with respect to radial distance from the center thereof.
